(57) **CLAIM**

The ornamental design for a corrugated plate for pallet, as shown and described.

DESCRIPTION

FIG. 1 is a perspective view of a corrugated plate for pallet, showing my new design;

FIG. 2 is a front elevational view thereof, the rear elevational view being symmetrical;

FIG. 3 is a top plan view thereof;

FIG. 4 is a bottom plan view thereof; and,

FIG. 5 is a right side elevational view thereof; the left side being symmetrical.

The plate is shown broken away in FIGS. 1,3,4 and 5 to show indefinite length.
